UNITED STATES PATENT OFFICE.

GEORGE MAYERLE, OF SAN FRANCISCO, CALIFORNIA.

LETTER FOR SIGNS.

1,089,003.

Specification of Letters Patent.

Patented Mar. 3, 1914.

Application filed October 21, 1911. Serial No. 655,862.

To all whom it may concern:

Be it known that I, GEORGE MAYERLE, a citizen of the United States, residing in the city and county of San Francisco and State 5 of California, have invented new and useful Improvements in Letters for Signs, of which the following is a specification.

This invention relates to a sign and particularly pertains to the construction of letters and characters such as are employed in 10 outdoor advertising signs.

It is the object of this invention to provide a letter or character for signs which is designed and constructed in such a manner 15 as to produce a scintillating or coruscating effect and thereby attract the eye.

A further object is to provide a letter or character for outdoor signs, in which the field or surface of the letter will be constantly 20 changing or moving, so as to have an agitated or fluttering appearance.

Another object is to provide means in a sign of the above character in which the agitated or coruscated effects are obtained by 25 the wind or currents of air.

The invention consists of the parts and the construction and combination of parts, as hereinafter more fully described and claimed, having reference to the accompanying 30 drawings, in which—

Figures 1 and 2 are front elevations of letters constructed in accordance with this invention. Fig. 3 is a detail side elevation of a letter showing the manner of suspending 35 same from a cable. Fig. 4 is a detail in perspective of one of the blades or vanes employed in this invention.

In the drawings A is the frame work constituting the outline of a letter, which frame 40 work may be formed of rods, wire or similar materials, as shown in Figs. 1, 2 and 3.

The frame work A is designed to be suspended from a cable 2, as shown in Fig. 3, a hook 3 mounted on the upper end of the 45 frame A engaging a sleeve 4 mounted to rotate on the cable 2.

The essence of this invention resides in disposing a series of blades or vanes 5 in the field of the letter; the blades or vanes 5 being pivotally mounted in any 50 suitable manner on the frame work A. In

this case they are shown as supported upon rods or shafts 6 carried by the framework A.

An object of the invention is to provide 55 an attractive letter for signs having the blades or vanes mounted in the framework thereof in such proximity as to have them constitute substantially the entire body of the letter. In order that this may be accomplished, the distance between the adjacent axes is made but slightly larger than the radius of the vanes. By this arrangement 60 it is obvious that the edges of the adjoining blades will nearly touch during the 65 time in which they are disposed in the plane of the frame, and thereby form the main body of the letter.

In Figs. 1, 2, 3 and 4 of the drawings, the blades are shown as S-shaped in end elevation and pivoted on their axes. 70

In Figs. 1 and 4 the blades are shown as mounted to rotate around vertical axes, while in Figs. 2 and 3 they are positioned to rotate around horizontal axes; it being 75 obvious, however, that the arrangement of the blades is subject to great variation. It is also obvious that the shape or outline of the blades is capable of considerable variation, and that various shaped and positioned 80 blades may be mounted in the field of each letter. The letters thus formed are designed to be suspended from the cable 2 in exposed positions, so that the wind and currents of air will act to rotate the blades 85

5 and at the same time swing the letter to and fro on the cable 2. The hook 3 being loose on the sleeve 4, and the sleeve 4 being loose on the cable 2, admits of a free swinging movement of the letter, relieves the cable 2 of strain due to wind pressures, and reduces frictional wear on the cable by the swinging of the letter. If it is desired to mount the letter in a stationary position, the pivotal mounting, consisting of the hook 90 95 3 and sleeve 4, may be dispensed with.

By forming the blades 5 with a reflective surface, such as mirrors, a scintillating or coruscating effect will be produced by the rotating blades, when rays of light are directed thereon, and by coating one side of the blades with one color and the opposite 100

side with another color, an agitated or fluttering appearance on the field of the letter will be obtained.

The movements of the blades or vanes 5 act to attract the eyes of passersby, thereby drawing attention to the sign and thus increasing its advertising value.

Having thus described my invention, what I claim and desire to secure by Letters

10 Patent is:—

1. In a sign in combination, a framework comprising a rod bent in the form of a letter, a series of rotatably mounted blades arranged to form a letter and mounted within 15 said frame, each of said blades being formed in such manner as to cause the blades to be rotated by air currents and to exhibit first one side of the blade and then the other side of the blade to the observer standing in any position from where said sign can be read, said blades being so positioned 20 as to have their adjacent edges nearly touch when in the plane of the frame, one side of each blade being of one color and the other

side of each blade being of a different color, 25 substantially as described.

2. In a sign in combination, a frame work comprising a rod bent in the form of a letter, a series of blades mounted on horizontal axes and arranged to rotate within said frame-work, each of said blades being formed in such manner as to cause the blades to be rotated by air currents and exhibit first one side and then the other to an observer, each of said blades being provided on one side 35 with a reflecting surface adapted to reflect rays of light to the ground in the paths of passersby to thereby attract their attention, the blades being arranged sufficiently close to nearly touch when in the plane of the 40 frame.

In testimony whereof I have hereunto set my hand in the presence of two subscribing witnesses.

GEORGE MAYERLE.
